UNITED STATES PATENT OFFICE.

JOHN D. MARTIN, OF NEW STRAITSVILLE, OHIO.

FURNACE.

Application filed November 12, 1923. Serial No. 674,176.

To all whom it may concern:

Be it known that I, JOHN D. MARTIN, a citizen of the United States of America, and a resident of New Straitsville, Perry County, State of Ohio, have invented certain new and useful Improvements in Furnaces, of which the following is a specification.

This invention relates to coal-burning furnaces, and particularly to furnaces of a circular grate type with automatic means for introducing the fuel from underneath and for removing the ash and siftings.

One object of this invention is to provide a construction in which the mechanical parts are safeguarded against extreme heat. Further objects are to provide for proper distribution of fuel over the grate and to prevent disarrangement of the mechanical action or stoppage through fusion of slag to the furnace walls or warping of the grate rings or wear of the parts.

In the accompanying four sheets of drawings which form a part of this specification,

Figure 1 is a vertical section through a furnace embodying this invention on the line I—I of Fig. 2;

Fig. 2 is a horizontal section through the furnace on the line II—II of Fig. 1;

Fig. 3 is a vertical section drawn to a larger scale showing the portion within the furnace, the grate and the conveyor tube also being shown in section; and

Fig. 4 is a plan of the portion of the apparatus within the furnace, showing the ash-ring and omitting the grate rings.

This invention is illustrated in connection with a brick-kiln in which a number of furnace units are each built partly in the enclosing wall of the kiln.

For each unit a semi-circular niche is made in the inner side of the wall 10 and the circle is completed by a semi-circular wall 11 which is carried to a height of about five feet. The semi-circular walls are not bonded to the furnace wall and are independently renewable. There is a lower opening through the kiln wall through which the conveying apparatus passes and there is an upper opening closed by a furnace door through which the condition of the fuel bed can be inspected. The lower opening is bricked up around the apparatus so that the entrance of air for combustion may be better controlled. A ledge 12

in the furnace wall supports a frame ring 13. Curved arms 14, 14 extend inwardly from this ring to a central hub 15 to which a two-chambered casting 16 is bolted. A vertical fuel-conveyor tube 17 is screwed into an opening in the top wall of this casting and a horizontal fuel-conveyor tube 18 is screwed into a side wall of the same chamber of the casting, and extends through the wall of the kiln to a point outside the furnace. It is customary to rivet light longitudinal strips to keep the coal from turning with the screws. An ash-ring 19, as large as or slightly larger in outside diameter than the frame ring, has curved arms 20, 20 extending inwardly to a central hub 21 which is carried by the vertical conveyor tube which serves as an axle therefor. Slots in the side of the hub let out any coal siftings which may get into the bearing. By reason of the arms of the ash-ring and of the supporting ring being curved they will not be unduly strained with the expansion or warping of the rings by the heat of the furnace which will be more direct on the rings than on the arms. As the ash-ring is supported through its hub and not at its rim, expansion or warping will not bring it into contact with anything to impede its movement and there is always a free passage for air around it to keep it from being unduly heated. The top of the ash-ring is inclined about eight degrees and has radial teeth or flutes to insure that the ash thereon is carried around with the ring. A sprocket 22 is mounted on the hub by which the ash-ring is revolved, or it may be cast solidly therewith. A conical grate is formed above the ash-ring by a series of superimposed grate rings 23, 23 of progressively diminishing diameter. They overlap sufficiently so that the angle of repose of the fuel from the outer edge of any ring inwardly will not reach the inner edge of the underlying ring. The topmost ring is set below the top of the central hub and the falling of siftings in quantity between the ring and the hub is thereby prevented. Three legs or pins 24, 24 on the underside of each ring support it from the ring underneath and leave a horizontal passage for air. This three-point support avoids any instability arising through the warping of the rings. Three longer pins 25, 25 center each ring from the one underneath. As the grate rings are supported wholly from

the ash-ring they will revolve with it. On the upper side of the lowermost grate rings are lugs 26, 26 which engage the bed of fuel and insure that the fuel will be carried 5 around with the grate. There are air-holes through these lugs to keep them from burning off. In the vertical fuel-conveyor tube is a vertical helical fuel-conveyor 27. This rests on a partition wall 28 in the two-chambered casting which takes the weight and thrust. A sleeve 29 tapped into the partition wall and supported thereby projects upwardly into a hole in the lower end of the vertical conveyor and serves as a guide 10 therefor. This sleeve prevents fine coal from working through the bearing into the lower chamber. Above the end of the sleeve the hole in the vertical conveyor is square, and a shaft 30 passes through the sleeve and 15 has a square upper end 31 which engages the square part of the hole in the conveyor. The shaft 30 should be hollow to provide at its top for lubricating the joints between the sleeve and the shaft and the shaft and 20 the sleeve and the conveyor. In the lower chamber are two bevel gears in which the following gear 32 is attached to the vertical shaft and the driving gear 33 is on the end of a horizontal shaft 34. The square end 25 of the vertical shaft does not bottom in the hole in the conveyor so that settling of the conveyor with wear will bring no end pressure on the shaft which would tend to throw the bevel gears out of proper mesh. 30 Siftings will accumulate in the pit around the two-chambered casting, but on the front side they will not accumulate above the horizontal shaft for this is provided with an ash-conveyor helix 35 which will take ashes 35 away from the mouth and will draw the siftings out of the pit on the front side down to its level. In other parts of the pit the siftings cannot accumulate higher than scrapers 36, 36 which are carried around 40 with the revolving grate and ash-ring and carry out further accumulation of siftings around to the front side over the ash-conveyor. There will therefore be an air space 45 preserved above the scrapers and under the grate which is clear of siftings. Air is forced into this space through an opening 37 in the frame ring. The air flow is in the direction in which the grate and the scrapers 50 rotate and assists the scrapers in carrying the siftings around to the front side and feeding them to the ash-conveyor. The air is forced between the grate rings and through the fuel bed. There is also some 55 escape of air around the outer edge of the ash-ring through which secondary air is supplied above the fuel bed for completing the combustion of unconsumed gases arising from the bed. In practice the forced draft will be adjusted slightly in excess of the pull of the stack so that there will be a

slight tendency of the burning gases to blow out around the cracks of the furnace door. The supply of secondary air is therefore wholly from the forced draft. It is better distributed than if drawn in through the 70 furnace door and entirely envelops the fire. Also since it enters next to the hot furnace wall it will be heated thereby to combustion temperature before coming into contact with the combustible gases from the fuel bed. 75 This air also slightly cools the furnace wall where fused ash might be likely to touch it and prevent the ash from forming adhering clinkers.

A revolving ash-scraper 38 removes the 80 ashes from the ash-ring. It has a more positive action than a fixed scraper, no one arm is in the fire long enough to be injured by the heat and besides it is cooled by the secondary air from the forced draft. The 85 ashes as scraped off fall to the mouth of the pit. They are in part carried out therefrom by the ash-conveyor to a point where they are easily reached for removal with a shovel.

Power for continuous operation of the 90 moving parts is supplied from a shaft 40 in sections surrounding the kiln and connected by universal joints 41 41. Power is transferred from each section to the adjacent furnace apparatus through a pair of 95 bevel gears, one of which 42 is on the driving shaft and the other of which 43 is attached to the end of the shaft of a horizontal helical fuel-conveyor 44 which leads from the hopper 45 to the base of the vertical fuel 100 conveyor. The gear on the power shaft is driven through a pair of dogs 46, 46 one of which is attached to the shaft and the other of which is attached to the gear. These dogs are connected by a wooden pin 46^a so 105 that in case the conveyors of any furnace should become blocked, connection will give way at this point where it can easily be restored and breakage of any part not readily replaceable is avoided.

A pair of spur gears, one of which 47 is attached to the shaft of the horizontal helical conveyor, and the other of which 48 is the smaller of the two and is attached to the shaft of the ash-conveyor, transmits 115 power to the vertical fuel conveyor. As the gears are of unequal size the vertical fuel conveyor will be driven faster than the horizontal fuel conveyor and the vertical fuel conveyor will be certain to take away 120 all of the fuel delivered to it by the horizontal fuel conveyor so that choking at the point of transfer will be avoided without making the vertical conveyor pipe larger and encroaching on the effective grate 125 area.

A worm 50 on the shaft of the helical ash-conveyor drives a worm-wheel 51. The worm-wheel drives a pin disk 52 in conjunction with which is a second pin disk 53. 130

A pin of one disk is connected to a pin of the other disk by an easily fractured link 54, which will break before other parts in 5 case the grate or ash-ring or scraper should be blocked. One pin disk preferably has one more pin around its circumference than the other. In consequence, should it be necessary to replace a link, but a small part of a revolution will ever need to take place 10 before two pins will be in proper relation to receive a new link. The second pin disk connects to a sprocket 55 from which a chain 56 connects to the sprocket which revolves the ash-ring and the grate. One run of the 15 chain engages a sprocket 57 which is attached to the revolving ash-scraper.

The apparatus proportioned as shown is suitable for a furnace about forty inches in diameter but the invention is applicable to 20 furnaces larger or smaller than this and which are operated singly as well as in conjunction with others. The apparatus is driven so that the horizontal fuel conveyor will make about four revolutions a minute. 25 A good ratio between the horizontal and the vertical fuel conveyors will make about twenty to twenty-eight revolutions. The ash-ring and grate will require about fifteen minutes for a revolution. Adherence to 30 these speeds, however, is not essential to the invention. The vertical conveyor revolves more rapidly than is necessary for the feeding of fuel, as one of its other functions is to stir up the fuel bed at the apex of the cone to insure a more even distribution on 35 the different slopes.

I claim—

1. In a furnace, a conical grate, an underlying ash-ring, a scraper with radiating arms for removing ashes from the ash-ring, and means for revolving the ash-ring and the scraper.
2. In a furnace, a conical grate, an underlying ash-ring, a scraper for removing ashes 45 from the ash-ring, a helical conveyor under-

lying the scraper for conveying the ashes, and means for revolving the ash-ring and the conveyor.

3. In a furnace, a conical grate, an underlying ash-ring, a vertical helical fuel-conveyor, a bevel-gear transmission underlying the fuel-conveyor, a scraper for removing ashes from the ash-ring, and a horizontal helical ash-conveyor which underlies the scraper and through which power is communicated to the bevel-gear transmission. 50

4. In a furnace, a conical grate, an underlying ash-ring, a vertical helical fuel-conveyor, a bevel-gear transmission underlying the fuel-conveyor, a scraper for removing ashes from the ash-ring, a horizontal helical ash-conveyor which underlies the scraper through which power is communicated to the bevel-gear transmission, and means for revolving the ash-ring and the conveyors. 55

5. In a furnace, a conical grate, a horizontal helical fuel conveyor, a vertical helical fuel conveyor through the center of the grate of as small diameter as the horizontal conveyor and receiving fuel therefrom, and means for driving the vertical conveyor more rapidly than the horizontal conveyor. 70

6. In a furnace, a conical grate, an underlying ash-ring, a scraper for removing ashes from the ash-ring, a vertical helical fuel-conveyor through the center of the grate, a bevel gear transmission underlying the vertical fuel-conveyor, a horizontal helical fuel-conveyor for delivering fuel to the vertical conveyor, a horizontal helical ash-conveyor which underlies the scraper and through which power is communicated to the bevel gear transmission, and a driving connection between the shafts of the two horizontal conveyors the ratio of which is such in connection with the bevel gear transmission that the vertical fuel-conveyor will be driven more rapidly than the horizontal fuel-conveyor. 75

JOHN D. MARTIN.
